SOOT BLOWER SEAL

Robert Hudson Wager, Maplewood, N. J.

Application December 22, 1944, Serial No. 569,372

4 Claims. (Cl. 285—22)

1

Difficulty has heretofore been encountered in providing durable packing means for establishing fluid-tight seals around elements extending into enclosures containing hot gases, notably soot blowing elements extending through boiler furnace walls, and insofar as I am aware, no packing material has been produced which will effectively pack against escape of gases and at the same time resist the temperatures encountered, for any reasonable length of time. My invention, however, overcomes the difficulty by providing a novel construction for cooling the packing box and keeping the hot gases away from the same to a large extent, thus greatly diminishing the heat which the packing material must resist and consequently prolonging the life of the packing.

Figure 1 is a front elevation, partly in section, showing the invention applied.

Fig. 2 is a horizontal sectional view on line 2—2 of Fig. 1.

Fig. 3 is an enlarged vertical section on line 3—3 of Fig. 2.

Fig. 4 is a perspective view of one of the herein-after described rings.

Fig. 5 is a horizontal sectional view partly in top plan, showing a somewhat different form of construction.

Preferred forms of construction have been illustrated in the drawings and will be rather specifically described, with the understanding, however, that within the scope of the invention as claimed, variations may be made.

The structure shown in Figs. 1 to 4, will first be described. In the form of the invention shown in these views, a front plate 10 is provided, designed primarily to be secured by bolts or the like 11 against the outer end of a sleeve 12 extending through a boiler front or other wall 13, the rear side of said plate 10 having a seat for a gasket 14. The plate 10 is formed with a central opening 15 of circular outline, and an outer continuous side wall 16 surrounds this opening at the inner side of the plate 10, said wall 16 being preferably integrally joined to said plate. An end wall 17 is integrally connected with or otherwise secured to the inner end of the side wall 16, said end wall having a central opening 18 of less diameter than the opening 15 of the front plate 10. An inner cylindrical side wall 19 extends through the opening 15 and abuts the end wall 17, said inner wall 19 being welded at 20 to the front plate 10. The walls 16 and 19 are spaced apart to provide a chamber 21 to receive a cooling fluid, preferably air under pressure, and the front plate 10 is formed with one or more inlets 22 for said cooling fluid. Two of the inlets 22 are shown, a supply pipe 23 being connected with one of said inlets while the other is simply plugged as shown at 24.

Circumferentially spaced ports 25 are formed

2

through the inner wall 19 near the end wall 17, said ports extending from the outer to the inner side of said wall and being in communication with the chamber 21. Within the confines of the wall 19 and in contact with the end wall 17, is a ring 26, said ring having a peripheral channel 27 in communication with the ports 25. The ring 26 is also formed with radial ports or channels 28 which extend from the channel 27 to its interior.

10 In the present disclosure, the channel 27 opens not only through the periphery of the ring 26, but through the side of said ring remote from the end wall 17, and the ports 28 are simply grooves in said side of the ring. The channels and ports, however, could be of other forms. The inner diameter of the ring 26 is such as to clear the element 29 to be packed, thus leaving a fluid-conducting passage 30 between said ring and element. Similarly, the opening 18 of the end wall 17 is of such diameter as to clear the member 29, leaving a fluid passage 31 between the two. The member 29, in the present disclosure, is the blower element of a soot blower for cleaning soot from boiler tubes.

25 A ring 32 lies against the side of the ring 26 remote from the end wall 17, and forms an abutment for the rearmost of a plurality of packing rings 33 which surround the element 29 within the confines of the inner wall 19. A gland 34 extends into the outer end of the wall 19 and is associated with suitable adjusting means 35 mounted on the front plate 10. Adjustment of the gland 34, of course, compresses the packing 33 and holds it tightly around the element 29.

35 Air under pressure is forced into the chamber or jacket 21 through the pipe 23 and inlet 22, and from said jacket or chamber, the air flows inwardly through the ports 25 of the inner wall 19, into the peripheral channel 27 of the ring 26.

40 From this channel, the air flows inwardly through the ports 28 to the passage 30 and through this passage to the passage 31, from which it discharges around the element 29, as indicated by the arrows in Fig. 2. The relatively cool air, in

45 circulating around the wall 19 and in flowing inwardly through said wall, keeps the latter relatively cool and thus aids in keeping the packing 23 comparatively cool and protecting it against heat damage. Also, the discharge of air around

50 the element 29 from the passage 31, tends to blow the hot gases away from the packing box and prevents them from entering the inner end of the box and burning the packing. Therefore, conventional packings may be used without danger 55 of injury from the hot gases, insuring long life and overcoming the previous difficulty.

The construction so far described is used principally when sufficient clearance exists between the blower head 36 and the boiler wall to accommodate the air supply pipe 23 and the gland

34 with its adjusting means 35. For installations where there is insufficient clearance for these elements, the construction disclosed in Fig. 5 is employed. In this view, the outer wall 16^a is provided at its outer end with a lateral attaching flange 10^a, and an end wall 17^a is integral with the inner end of said outer wall 16^a. An inner side wall 19^a abuts the end wall 17^a at its inner end, the outer end of said inner wall 19^a being formed with a lateral flange 19^b welded at 20^a to the outer wall 16^a, said flange 19^b being inwardly spaced from the outer end of said wall 16^a to allow the packing compressing gland 34^a and its adjusting means 35^a to be housed within the confines of the outer portion of said wall 16^a. The flange 19^b is apertured for connection with the air supply pipe 23^a.

All parts within the confines of the inner wall 19^a are substantial duplicates of those within the wall 19 and hence, require no individual description. The assemblage is cooled in the same way by circulation and discharge of air under pressure and the same advantages flow from such cooling.

While preferences have been disclosed, attention is again invited to the possibility of making variations within the scope of the invention as claimed.

I claim:

1. A packing box comprising a front plate having an opening, a continuous outer side wall surrounding said opening at the inner side of said front plate and rigidly secured to the latter, an end wall secured to the inner end of said side wall, said end wall having an opening aligned with and of smaller diameter than the opening of said front plate, a cylindrical inner side wall extending through said opening of said front plate and secured to the latter, the inner end of said inner side wall being in contact with said end wall around the opening of the latter, said outer and inner side walls being spaced apart to provide a chamber for a cooling fluid, said front plate having a fluid inlet for said chamber, said inner side wall having a port from said chamber to its interior near said end wall, a gland in the outer end of said inner wall, packing means between said gland and said end wall, and means for conducting the cooling fluid from the aforesaid port of said inner side wall to said opening of said end wall.

2. A packing box comprising a continuous outer side wall having a lateral attaching flange on its outer end, an end wall secured to the inner end of said outer side wall and having an opening, an inner cylindrical side wall within the confines of said outer wall, said inner side wall having a lateral flange on its outer end secured to said outer side wall and spaced inwardly from the outer end of said outer side wall, said outer and inner side walls being spaced apart to provide a chamber for a cooling fluid, said flange of said inner side wall having a fluid inlet for said chamber, said inner side wall being in contact with said end wall around said opening of the latter and having a fluid port communicating with said chamber, a gland in the outer end of said inner side wall, packing means between said gland and said end wall, and means for conducting the fluid from said port of said inner side wall to said opening of said end wall.

3. A packing box comprising a front plate for attachment to a support, said front plate having an opening of circular outline, a continuous

outer side wall surrounding and spaced outwardly from the edge of said opening, said outer side wall being disposed at the inner side of said front plate and having its outer end integrally joined to said front plate, an inner end wall integral with the inner end of said side wall, said end wall having an opening aligned with and of smaller diameter than the opening of said front plate, a cylindrical inner side wall extending through said opening of said front plate and secured to the latter, the inner end of said inner side wall being disposed against said end wall and spaced around said opening of the latter, said inner and outer side walls being spaced apart to provide a chamber for a cooling liquid, said front plate having a fluid inlet for said chamber, said inner side wall having circumferentially spaced ports from said chamber to its interior and located near said end wall, a ring abutting the inner side of said end wall and disposed within said inner side wall, said ring having passages for conducting the cooling fluid from said ports of said inner side wall to said opening of said end wall for discharge around the element to be packed, a gland in the outer end of said inner side wall, and packing means between said ring and said gland.

4. A packing box comprising a continuous outer side wall having an integral lateral attaching flange on its outer end, an inner end wall integral with the inner end of said outer side wall and having a central opening, an inner cylindrical side wall within the confines of said outer side wall and having its inner end disposed against said end wall around said opening, the outer end of said inner side wall being spaced inwardly from the outer end of said outer side wall and having an integral lateral flange secured to said outer side wall, the two side walls being spaced apart to provide a chamber for a cooling fluid, said flange of said inner side wall having a fluid inlet for said chamber, said inner side wall having circumferentially spaced ports from said chamber to its interior and located near said end wall, a ring abutting the inner side of said end wall and disposed within said inner side wall, said ring having passages for conducting the cooling fluid from said ports of said inner side wall to said opening of said end wall for discharge around the element to be packed, a gland in the outer end of said inner side wall, packing means between said ring and said gland, and adjusting means for said gland surrounded by the outer end portion of said outer side wall.
